United States Patent Office.

EDMUND A. SEELEY, OF SCOTCH PLAINS, NEW JERSEY.

Letters Patent No. 96,039, dated October 19, 1869.

IMPROVED ATTACHMENT TO ROLLS FOR CALENDERING PAPER-BOARDS.

The Schedule referred to in these Letters Patent and making part of the same

I, EDMUND A. SEELEY, of the town of Scotch Plains, in the county of Union, and State of New Jersey, have made certain Improvements in Attachment to Rolls for Calendering Paper-Boards, of which the following is a specification.

My improvement relates to the means for the application of moisture and heat by steam to the surface of either or both sides of the board, as it enters between the rollers.

The accompanying drawings represent, in—

Figure 1, the stand and the rolls, with the new attachment, in a front view of the same.

Figure 2 is a sectional view of the rolls, the board, and the new attachment.

A is the stand. B and C the rolls, such as are in common use. E and F are small metal pipes, placed

parallel with the rolls, as close to the board and the rolls as they can conveniently be. Small perforations are made in the metal pipes, and are so placed as to direct the steam to the boards, as near their contact with the rolls as possible. g designates the board.

I disclaim all application of steam to boards by the means of boxes, or anything of that kind.

I claim as my improvement, and desire to secure by Letters Patent—

The small perforated metal pipes E and F, when used in combination with the calenders for finishing paper-boards, in the manner herein specified.

EDMUND A. SEELEY.
